UNITED STATES PATENT OFFICE.

ELMER J. BRYANT, OF WOONSOCKET, RHODE ISLAND, ASSIGNOR TO THE TAFT-PEIRCE MANUFACTURING COMPANY, OF WOONSOCKET, RHODE ISLAND, A CORPORATION OF RHODE ISLAND.

DESIGN FOR AN EXTERNAL-LIMIT GAGE.

49,203.

Specification for Design.

Patented June 20, 1916.

Application filed January 8, 1915. Serial No. 1,254. Term of patent 14 years.

To all whom it may concern:

Be it known that I, ELMER J. BRYANT, a citizen of the United States, a resident of Woonsocket, in the county of Providence, State of Rhode Island, have invented a new, original, and ornamental Design for an External-Limit Gage, of which the following is a specification, reference being had to the accompanying drawings, forming a part thereof.

Figure 1 illustrates a plan view of my design. Fig. 2 illustrates an end view of my design.

In the design illustrated in the drawings all of the flat surfaces, on each side of the gage comprising the rectangular-shaped areas, are substantially co-planer. The ribs

on the inner edges of the jaws are rounded and of a slightly less thickness than the thickest part of the gage, which is determined by the co-planar surfaces previously mentioned. The body portion of the gage extending between the previously mentioned parts is the thinnest portion of the gage and is substantially of uniform thickness, and has rounded exterior edges as is indicated in the drawings.

I claim:—

The ornamental design for an external limit gage, as shown and described.

ELMER J. BRYANT.
